UNITED STATES PATENT OFFICE

LOUIS LICHTMAN, OF NEW YORK, N. Y., ASSIGNOR TO CHROMEPLATE, INC., OF NEW YORK, N. Y., A CORPORATION OF NEW JERSEY

HANGER FOR ARTICLES TO BE PLATED

Application filed October 3, 1929. Serial No. 397,028.

This invention is an improvement in hangers for articles to be plated, and more particularly in a hanger for chromium plating, enabling the article to be supported in the 5 most favorable position for receiving the deposit.

In plating articles, such as spoons and the like, it is somewhat difficult to obtain good contact between the article and the cathode, 10 with a minimum of contact, and to support the article firmly against liability to displacement.

Wherever there is contact between the article and the support for the same, which is 15 electrically connected with the cathode, the portion of the article covered in the contact is not coated. For this reason, it is desirable that the article be supported in such manner that it may be moved slightly during the 20 deposition to expose the surface formerly covered in the contact.

One of the primary objects of the present invention is the provision of a hanger, of a nature such that close contact is provided 25 between the hanger and the article, while at the same time the article may be moved with respect to the hanger during the plating operation, to expose the surface previously covered to the action of the electrolyte.

30 Another object is the provision of a hanger in the form of a one piece conductor, of a character such that the resiliency thereof is not materially impaired by use.

Another object is the provision of a hanger 35 wherein contact with the article is made at opposite sides thereof, at points spaced apart from each other, and resiliently to enable good conduction with the capability of manually moving the article for the purpose above 40 mentioned.

Another object is the provision of a rack of simple inexpensive construction adapted 45 to support a maximum of articles in a minimum of space.

With these and other objects in view the invention consists in the construction and 50 novel combination of parts fully described hereinafter, illustrated in the accompanying drawings, and pointed out in the claims 55 appended hereto, it being understood that va-

rious changes in the form, proportion, size and minor details of construction within the scope of the claims, may be resorted to without departing from the spirit of the invention.

55 In the drawings forming a part hereof:—

Fig. 1 is a transverse vertical section of a tank provided with the improved hanger.

Fig. 2 is a perspective view of one of the cross bars with hangers or holders connected 60 therewith.

Fig. 3 is a plan view of a part of a cross bar with a modified form of holder or hanger.

The present embodiment of the invention is shown in connection with the plating tank 65 1 of usual construction, having one or more cross bars 2 extending across the tank, either longitudinally or transversely, and adapted to support the rack, having hangers in accordance with the present invention.

70 The rack comprises a substantially U-shaped frame, composed of a body 3, and arms 4, each arm having a hook 5 at its upper end for engaging a cross bar, so that the hanger depends into the electrolyte in the 75 tank. The arms 4 are connected at suitable intervals by cross bars 6, and the cross bars carry the holders or hangers of the invention.

Each of these holders or hangers is a substantially U-shaped member, formed of wire 80 of suitable gauge, the wire being bent to form an open ring or loop 7, with the arms 8 extending along side each other in spaced relation from the ends of the ring. The ends of the arms remote from the body are soldered 85 or otherwise secured to a cross bar 6, the connection being indicated at 9.

Each arm is provided, near the ring 7, with 90 an outwardly bent portion, forming a notch 10 on the inner face of the arm, and the notches of the two arms are in register. The ring 7 is of a size sufficient to permit the passage of the handle of a spoon 11, or like article, such for instance as a fork or knife, 95 and the articles are inserted by passing them upwardly through the ring or loop, and between the arms, with the plane of the handle portion of the article substantially parallel with the arms. At the notches 10, the article 100

is turned at substantially right angles in the dotted line position shown in Fig. 2.

The arms are so spaced that the bottoms of the notches are distant from each other 5 less than the width of the article to be held, and the material of the holder is resilient, so that when forced apart as above mentioned, they will grip the article firmly through their resiliency, holding it against 10 accidental displacement, but permitting movement thereof when sufficient force is exerted.

In Fig. 3, the holder is slightly different in form, being designed to support two articles, 15 or to support a single article in either of two positions. In this arrangement, the holder is of wire bent into U or hair-pin shape. The arms 12 of the holder extend along each other in spaced relation, to a connection 13 with the cross bar 14 of the rack. Each arm has an outwardly bent portion 15 near the end remote from the cross bar, the outwardly bent portions 15 cooperating to 20 form a ring or loop open at opposite sides.

25 At each side of the ring or loop, each arm has outwardly bent portions 16 and 17, respectively, forming notches similar to the notches 10 of the arms 8, and similarly spaced. The corresponding notches are in 30 register, and it will be apparent that two articles may be supported, one by the notches 16 and another by the notches 17, or either set of notches may support a single article.

What is claimed as new is:—

35 1. In a device of the class described, a holder for articles to be electro-plated, comprising a substantially U-shaped member including resilient arms lying alongside each other and connected at one end, the other ends 40 of the arms being adapted for connection with a support for the member, said arms having cooperating means near their said connection to engage the opposite edges of an article to be plated, and having registering 45 outwardly bent portions adjacent to said means to facilitate the engagement of the article therewith.

50 2. In a device of the class described, a holder for articles to be electro-plated, comprising a substantially U-shaped member including resilient arms lying alongside each other and connected at one end, the other ends 55 of the arms being adapted for connection with a support for the member, said arms having cooperating means near their said connection to engage the opposite edges of an article to be plated, and having registering outwardly bent portions adjacent to said 60 means to facilitate the engagement of the article therewith, said holder being of conducting material and adapted for connection with the cathode of a plating bath.

65 3. In a device of the class described, a rack for articles to be electro-plated, including a plurality of bars, each carrying a plurality

of U-shaped members, each member including arms lying alongside each other and connected at one end, the other ends of said arms being connected to the bar, said arms having cooperating means to engage the opposite edges of an article to be plated, and having registering outwardly bent portions adjacent to said means to facilitate the engagement of the article therewith.

4. A device of the class described, including arms lying alongside each other and integrally connected at one end, the other ends of the arms being adapted for connection with a fixed support, each arm having a plurality of outwardly-bent portions, the portions of each arm registering with those of the other arm, and one pair of outwardly-bent portions being adapted to permit the passage of a spoon-handle with its plane transverse to the length of the arms, and the other pair being adapted to grasp the edges of the handle, when it has been slipped between the arms with its plane in the direction of the length thereof, and turned transversely to the arms.

Signed at New York city, in the county of New York and State of New York, this 29th day of August, A. D. 1929.
